[57] CLAIM

The ornamental design for a pallet, as shown and described.

DESCRIPTION

FIG. 1 is a perspective view of a pallet showing my new design;

FIG. 2 is a top plan view thereof;

FIG. 3 is a side elevational view thereof, the opposite side elevational view being a mirror image of that shown;

FIG. 4 is a front elevational view thereof, the rear elevational view being a mirror image of that shown;

FIG. 5 is a sectional view thereof, taken along lines 5—5 of FIG. 3.

FIG. I

FIG. 2

FIG. 3

FIG. 4

FIG. 5
